UNITED STATES PATENT OFFICE.

HERBERT A. STREETER AND ROBERT C. CARNAHAN, OF CHICAGO, ILLINOIS, ASSIGNEES, BY DIRECT AND MESNE ASSIGNMENTS, TO STREETER CLIP & SPECIALTY CO., OF CHICAGO, ILLINOIS, A CORPORATION OF ILLINOIS.

BENDING MACHINE.

1,203,431.

Specification of Letters Patent. Patented Oct. 31, 1916.

Application filed June 24, 1912. Serial No. 705,391.

To all whom it may concern:

Be it known that we, HERBERT A. STREETER and ROBERT C. CARNAHAN, citizens of the United States, residing at Chicago, in the county of Cook and State of Illinois, have invented a new and useful Improvement in Bending-Machines, of which the following is a specification.

This invention relates to improvements in bending machines, and more particularly to bending machines for operating on clips, such as are used in connection with structural framework.

One object of the invention is to provide a power operated machine of the type above indicated, of large capacity, and adapted to operate on two sizes of clips at the same time without the necessity for adjusting any of the parts.

Another object of the invention is to provide a bender having an anti-friction roller on its active edge, which will be in direct contact with the article being bent during the bending operation, thus eliminating a great amount of friction, and consequent waste of power, as compared with former types of bending machines.

A third object of the invention is to provide driving mechanism for operating both benders of the machine, so as to give an oscillating motion thereto from a power shaft continuously driven in one direction only.

In the drawing forming a part of this specification, Figure 1 is a front view of a machine embodying our improvements. Fig. 2 is an end elevation of the machine, as viewed from the right of the structure shown in Fig. 1. Figs. 3 and 4 are vertical, sectional views, taken on the lines 3-3 and 4-4, respectively, of Fig. 1. Fig. 5 is a vertical, sectional view, taken on the line 5-5 of Fig. 6. Fig. 6 is a vertical, sectional view, taken on the line 6-6 of Fig. 5, and Fig. 7 is a detail, perspective view of the finished article after being operated upon in this machine.

In the drawing, A denotes a framework suitably adapted to support the various parts of the bending mechanism hereinafter described, said frame A, as shown, being provided with two spaced, vertically extending members A¹ and A², to which are journaled the various shafts hereinafter described.

Inasmuch as the bending mechanisms on each end of the machine are substantially identical, the description will be limited to parts of one of them, except in so far as it is necessary to describe the common driving mechanisms.

Each bending mechanism comprises a stationary forming mandrel 10 secured to a bracket 11, which, in turn, is removably secured to one of the upright members A¹ or A² of the frame. Adjustably mounted on each bracket 11 is a plate 12, provided with a retaining member 13 arranged parallel to the forming mandrel 10 and spaced therefrom, and between which is adapted to be placed the clip B, which, when introduced into the bending machine, has its wings B¹ and B² bent at right angles to the vertical portion B³, the portion B⁴ being bent or curved by the bender, as hereinafter described. Secured to the member 13 is a rod 14, on which is adjustably mounted a sleeve 15, to which is secured in turn a supporting table 16 upon which the clips B are adapted to rest and be supported during the bending operation.

Cooperating with each of the forming mandrels 10 is a pivoted bender, the latter comprising a head plate 17 keyed to a shaft 18, it being understood that the shaft 18 is common to the head plates at both ends of the machine, said head plate having a bender 118 adjustably secured thereto as by means of bolt and slot connections, which bender is in the form of a bracket having a laterally extending arm 19, and freely and rotatably mounted in the arm 19 is an anti-friction roller 20, the latter, as more clearly shown in Figs. 5 and 6, forming the active edge of the bender and adapted to bend the portion B⁴ of the clip around the mandrel 10 to the position shown in dotted line in Fig. 5. Power is derived from any suitable source, not shown, and is transmitted to the machine as by means of a belt 21 to drive continuously the pulley 22 loosely mounted on the power shaft 23, said pulley being provided with a clutch face member 24, with which is adapted to coöperate a clutch member 25, keyed to the shaft 23 and adapted to be moved into engagement with the clutch member 24, as by means of a pivoted lever 26 operated from a foot treadle 27, and normally held disengaged by means of a retracting spring 28 secured to the lever and

105

to a stationary part of the frame. Also keyed to the shaft 23 is a small pinion 29, meshing with a larger pinion 30, secured to the shaft 31, said shaft 31 being provided with two partial or segmental gears 32 and 33 set approximately at 100 degrees to each other, the segmental gear 32 being adapted to drive intermittently through the intermediary of a pinion 34, the gear 35 keyed to the shaft 18 so as to give the latter a partial revolution clockwise to rotate the bender in a forward direction at the right hand end of the machine, as viewed in Fig. 1. The segmental gear 33 is also adapted to rotate the shaft 18 a partial revolution intermittently by engaging the gear 36, also keyed to the shaft 18, but, as will be obvious, the direction of rotation given to the shaft 18 by the segmental gear 33 will be opposite to the direction of rotation given to it by the segmental gear 32, and these movements will be given alternately and intermittently, it being further understood that the segmental gears 32 and 33 are not only set 100 degrees apart, but each comprises less than a half gear in order to allow sufficient clearance between the disengagement of one segmental gear and the engagement of the other. In order to insure the stopping of the pivoted benders at the proper position at the end of their return movement, one of the head plates 17 is provided with a notch 17^a in which is adapted to engage a projection on the end of a spring controlled, pivoted lever 37, and adapted to be moved from engagement with the head plate 17 by means of a cam 38 secured to the shaft 31. In order to prevent overthrow of the benders, an adjustable friction brake 39 (see Fig. 4) is provided on the shaft 18, the friction brake being in the form of a split sleeve secured to the upright member A² of the frame.

From the foregoing description, it will be apparent that the machine may be set up with forming mandrels of different sizes at each end of the machine, and the retaining and supporting means for the clips adjusted for various sizes, and that the machine may operate simultaneously to bend clips of different sizes, where it is desired to employ an operator at each end of the machine, thus providing a machine of exceedingly high capacity as compared with the old type of hand operated bending machines for performing the same operations, and it will also be noted that the oscillating movement to each of the benders is derived from a power shaft adapted to be rotated in one direction only, thus obviating the necessity for reversing clutches or other complicated similar devices. It will also be noted from an inspection of the drawing and reading of the description, that the segmental gear 33 operates to move the benders in a forward direction, that is to bend the metal, at

a much slower rate than does the segmental gear 32 to return the bender to its starting position, and with this arrangement sufficient time is left at the end of the return movement of the bender for the operator or operators to insert the clips in proper position before the bending operation takes place. By employing the roller along the active edge of the bender, all danger of scraping or cracking of the clip is avoided, which hitherto has been a defect in bending machines, particularly those operating on light metal such as this machine is more particularly designed for.

We have shown one form of our improvements, but the same is merely illustrative, and it will be understood that various changes and modifications may be made in the details of the construction without departing from the spirit of the invention, and all changes and modifications are contemplated as fall within the scope of the claims appended hereto.

We claim:—

1. A clip bending machine including, in combination: a stationary mandrel; an oscillatable bender coöperating with said mandrel; and automatically operable power-driven means for moving said bender on its forward active stroke at a slower rate than on its return inactive stroke, substantially as specified.

2. A bending machine including, in combination: a stationary mandrel and a bender oscillatable about said mandrel and coöperating therewith; means for oscillating said bender; and a device automatically operable for stopping the bender in the proper position upon its return stroke, substantially as specified.

3. A clip bending machine including, in combination: a stationary mandrel; and means coöperating with said mandrel to bend a clip therearound, said means including an oscillatable head plate, a bracket adjustably mounted thereon and an antifriction roller mounted in said bracket, the antifriction roller forming the active edge of the bending means, substantially as specified.

4. A clip bending machine including, in combination: a stationary mandrel; an oscillatable bender coöperating with said mandrel; and means for supporting and retaining a clip in position while being operated upon, said means including members adjustable vertically and horizontally relatively to said mandrel to thereby adapt the machine for operating on clips of different sizes and types, substantially as specified.

5. A clip bending machine including, in combination: a stationary mandrel; an oscillatable bender coöperating with said mandrel; and power-driven means for moving said bender on its forward active stroke

at a slower rate than on its return inactive stroke, said means including oppositely rotating segmental gears driven from a common power shaft, substantially as specified.

5 6. In a machine of the class described, in combination, a pivotally mounted bender, a stationary forming mandrel, driving mechanism for automatically oscillating the bender and means adjustable relatively to the mandrel for retaining the article being operated upon in position.

10 7. In a machine of the class described, in combination, a stationary forming mandrel, a pivotally mounted bender, automatic mechanism for oscillating said bender and means adjustable relatively to the mandrel for retaining the article being operated upon in position, said bender and former being adjustable relatively to each other.

15 8. A clip bending machine including in combination, a mandrel and means coöperating with said mandrel to bend a clip thereabout, with said means including a member oscillatable about an axis parallel with the bend to be made in said clip and located at a side of said clip, a bending element carried by said member, and means for automatically oscillating said member and bender at predetermined intervals, substantially as 20 specified.

25 9. A clip bending machine including in combination, a stationary mandrel and means coöperating with said mandrel to bend a clip thereabout, said means including an oscillatable head plate, a bracket adjustably mounted thereon and a bending 30

member extending out from said head plate, substantially as specified.

10. In a clip bending machine, the combination of a shaft carrying a pair of offset bending elements, a mandrel for each element, a driving shaft, an intermittently operable gear connection between said driving shaft and said bending element carrying 40 shaft for imparting a partial working revolution to said benders about said mandrel, and a second intermittently operable gear connection between said shafts for rotating said bending element carrying shaft through 45 a partial idle revolution in opposite direction to its working stroke, substantially as specified.

11. In a clip bending machine, the combination of a shaft carrying a pair of offset bending elements, a mandrel for each element, a driving shaft, an intermittently operable gear connection between said driving shaft and said bending element carrying 50 shaft for imparting a partial working revolution to said benders about said mandrel, and a second intermittently operable gear connection between said shafts for rotating said bending element carrying shaft through 55 a partial idle revolution in opposite direction to its working stroke, substantially as specified.
